UNITED STATES PATENT OFFICE.

AXEL PERSON, OF ATTLEBORO, MASSACHUSETTS, ASSIGNOR TO HARVEY CLAP & CO.,
OF ATTLEBORO, MASSACHUSETTS, A PARTNERSHIP.

BRACELET CHAIN FOR WRIST WATCHES OR THE LIKE.

Application filed February 20, 1926. Serial No. 89,599.

This invention relates to construction for bracelet chains for wrist watches and the like. One of the objects thereof is to provide a construction of the above nature which is thoroughly practical and efficient. Another object is to provide a construction of the above nature having provision for expansion and which is neat and attractive in appearance under all conditions of use. Another object is to provide a construction of the above nature which is rugged and durable. Another object is to provide a construction of the above nature adapted dependably to hold a wrist watch or the like in place and conveniently detachable. Another object is to provide such a device which is simple in construction and capable of manufacture inexpensively. Other objects will be in part obvious or in part pointed out hereinafter.

The invention accordingly consists in the features of construction, combinations of elements, and arrangements of parts as will be exemplified in the structure to be herein-after described and the scope of the application of which will be indicated in the following claims.

In the accompanying drawing in which is shown one of the various possible embodiments of this invention,

Figure 1 is a top plan view;

Figure 2 shows an end portion of the bracelet chain in enlarged detail and partly in section, the section being taken along the line 2-2 of Figure 4;

Figure 3 is a section taken substantially along the line 3-3 of Figure 4;

Figure 4 is a bottom plan view of the parts shown in Figures 2 and 3;

Figure 5 is a section taken substantially along the line 5-5 of Figure 3, and

Figures 6, 7 and 8 are perspective views of coacting parts shown detached from one another.

Similar reference characters refer to similar parts throughout the several views of the drawing.

Referring now to Figure 1 of the drawing, there is shown a bracelet chain the body of which consists of a series of substantially abutting block links 10 which are connected together as will presently be described in detail, to form a flexible chain. At each end of the chain is provided an attaching device for the purpose of making connection with

a wrist watch or similar article to be held in place upon the wrist. As will be seen from Figures 2 and 3, the end members or links 11 and 12 of the chain are of greater length than the main block links 10 and slide beneath the attaching devices, as will be described, to permit expansion or lengthening of the chain.

Considering now the manner in which the block links 10 are constructed and connected together, referring to Figures 2 and 3, it will be seen that each of these block links is provided with upstanding side walls 13 and with upstanding end walls 14. The side walls 13 give the links the appearance of being solid blocks. As best shown in Figures 3 and 4, the block links 10 are joined together to form the chain by means of intermediate connecting links 15. The end walls 14 of the block links 10 pass through the connecting links 15 and are bent over into a plane substantially parallel with the top surfaces of the links. These bent over portions 14^a of the end walls are of such length that, in each block link they abut at their ends and thus form a smooth solid bottom surface for the links. In addition, the side walls 13 of the block links have portions 13^a bent over beneath the links and of such length that their edges abut the side edges 85 of the bent over portions 14^a. Thus, it will be seen that the block links are provided with a solid and smooth bottom surface to contact with the wrist of the wearer. Moreover, it will be seen in Figure 4 that the bent over parts 13^a as well as the bent over parts 14^a embrace the connecting links 15. In this manner a strong and serviceable construction is obtained.

The two connecting devices at the respective ends of the bracelet chain are preferably substantially identical so that one only need be described in detail. As was mentioned above, and as shown in Figures 2 and 3, the end link 11 is of substantially greater length than the main links 10 and is slideable beneath the outer surface of the end connecting device. The top wall of this connecting device is formed by a sheet metal member 16 which is provided with depending side walls 17. The left-hand end portion of the member 16, as viewed in the drawing, is extended outwardly and curved downwardly to form a hook 18. This part 16 with its side walls 17 and hooked portion 110

18 is clearly shown in perspective and in enlarged detail in Figure 6. The hook 18 is adapted for making connection with the bracket or cross-bar of the wrist watch.

5 The bottom wall of the connecting device is formed by a sheet metal member 19 which is shown in perspective in Figure 7 and in transverse section in Figure 5. The member 19 is provided at its side edges with projecting lugs 20 which fit into the notches 21 indicated in the side walls 17 of the part 16 in Figure 6. In assembling the parts, the member 19 is placed upon the member 16 with the lugs 20 in registry with the notches 21 and thereupon the parts 17^a of the side wall 17 are flanged over as shown in Figure 4, thereby clamping the members 19 and 16 together.

20 The end link 11 is shown in enlarged perspective in Figure 8 and is seen to be provided with side walls 22 corresponding in depth to the side walls 13 of the block links 10. Also this end member 11 is provided with an end wall 23 which is flanged over 25 and embraces a connecting link 15 as is shown in Figures 2 and 3. This end member 11 fits beneath the member 16 and between the side walls 17 thereof and is slidable longitudinally therein.

30 The member 19, at its middle portion, is arched upwardly toward the top member 16, as is best shown in Figure 5, leaving only sufficient space for the member 11 to slide therebetween. Thus, at the sides of the member 19 are provided a pair of longitudinal chambers or passages 24 and 25 in which are received spiral compression springs 26 and 27. These springs are held between a pair of ears 28 formed on the sliding member 11 and a pair of ears 29 formed on the bottom or base member 19. These springs thus urge the member 11 to slide inwardly into the connecting device or toward the hook 18. The bracelet may be extended by 40 pulling the member 11 outwardly and exposing a greater portion thereof, this action compressing the springs 26 and 27. As this expansion or lengthening of the bracelet occurs, no unsightly gaps appear, the surface 45 of the member 11 being simply exposed to a greater extent. The surface of the member 11 may be marked off to resemble a number of the block links 10 and is preferably provided with the same design or ornamentation 50 which is applied to the links 10.

55 The middle portion of the bottom member 19 is extended from its end remote from the hook 18, and this extended part or extension 30 of the member 19 is bent back upon itself 60 and toward the hook 18. This member 30 which may be termed a tongue, thus bent, tends to spring outwardly from the bottom surface of the member 19 or downwardly away from the top member 16. When the 65 parts are assembled, the end portion 30^a of

this spring member springs against the lip 18^a of the hook 18. This spring member 30 thus provides an effective lock for the hook, preventing slipping out from the grip of the hook of any part which is embraced thereby. 70

It will be seen that this spring lock is an integral part of the attaching device, being formed integral with the bottom member 19. The use of solder or other similar securing means is wholly avoided and the resulting 75 structure is of maximum strength, insuring dependable service.

In order to attach the hook 18 to the bracket of a watch or the like, or in order to release the hook, the member 30 is sprung 80 upwardly toward the upper member 16. In order to facilitate manipulation of the locking member, the end thereof is preferably provided with an extension 31 which projects upwardly through an opening 32 in the 85 member 16. At its upper end the part 31 is provided with a bent over flange 31^a which may be engaged conveniently to lift the spring lock upwardly.

It will be seen that the construction herein 90 provided is one which is strong and rugged throughout. The number of parts employed is kept at a minimum and the parts which are employed are so constructed and so joined together as to insure correct action 95 and dependable service. There is thus provided a construction which achieves the objects of this invention and accomplishes many advantages of practical importance.

As many possible embodiments may be 100 made of the above invention and as many changes might be made in the embodiment above set forth, it is to be understood that all matter hereinbefore set forth or shown in the accompanying drawings is to be interpreted 105 as illustrative and not in a limiting sense.

I claim as my invention:

1. A connector for bracelet chains or the like comprising, in combination, a box-like member having top, bottom and side walls, said top wall being extended and curved downwardly at one end to form a hook, a 110 sliding member in said box-like member, sliding thereinto from the end thereof remote from said hook, and a pair of springs within said box-like member urging said last member to slide thereinto, said bottom wall being bent upwardly at an intermediate longitudinal portion and forming with said side 115 wall a pair of longitudinal pasages in which said springs rest.

2. A connector for bracelet chains or the like comprising, in combination, a box-like member having top, bottom and side walls, 120 said top wall being extended and curved downwardly at one end to form a hook, a sliding member in said box-like member, sliding thereinto from the end thereof remote from said hook, a pair of springs with- 125 130

in said box-like member urging said last member to slide thereinto, said bottom wall being bent upwardly at an intermediate longitudinal portion and forming with said 5 side wall a pair of longitudinal passages in which said springs rest, and a spring tongue for said hook extending longitudinally of and beneath said bottom wall to the lip of said hook and accommodated in the recess in the bottom of said box-like member formed by said upward bend in said bottom wall.

3. A connector for bracelet chains or the like comprising, in combination, a box-like member having top, bottom and side walls, 15 said top wall being extended and curved downwardly at one end to form a hook, a slidable member in said box-like member, sliding thereinto from the end thereof remote from said hook, and a pair of springs within said box-like member urging said last member to slide thereinto, said bottom wall being bent upwardly at an intermediate longitudinal portion and forming with said 20 side wall a pair of longitudinal passages in which said springs rest, said bottom wall having a part extending outwardly from the end thereof remote from said hook and bent to form a spring tongue for said hook, said part being accommodated in the recess in the 25 bottom of said box-like member formed by said upward bend in said bottom wall.

4. A connector for bracelet chains or the like comprising, in combination, a member having a top wall, a bottom wall, and side walls, a member slidably resting within said 35 first member having a top wall and dependent side walls, said bottom wall of said first member being bent upwardly toward said top wall at an intermediate longitudinal portion thereof, said slidable member having 40 parts depending therefrom on either side of said bent-up portion, and a pair of springs one on either side of said bent-up portion and engaging said depending parts of said slidable member and urging the same 45 to slide into said first member.

5. A connector for bracelet chains or the like comprising, in combination, a box-like member having top, bottom and side walls, 50 said box-like member being shaped so that the interior thereof provides a plurality of spaced longitudinally extending chambers, a member longitudinally slidable within said box-like member, and a plurality of springs one positioned in each of said longitudinal 55 chambers and connected to urge said member to slide into said box-like member.

In testimony whereof, I have signed my name to this specification this ninth day of February, 1926.

AXEL PERSON.
